UNITED STATES PATENT OFFICE.

GOULD M. CROSBY, OF SEA VIEW, MASSACHUSETTS.

GARDEN FURNITURE.

Application filed October 15, 1924. Serial No. 743,710.

To all whom it may concern:

Be it known that I, GOULD M. CROSBY, a citizen of the United States, residing at Sea View, in the county of Plymouth and State 5 of Massachusetts, have invented certain new and useful Improvements in Garden Furniture; and I do hereby declare the following to be a full, clear, and exact description of the invention, such as will enable others 10 skilled in the art to which it appertains to make and use the same.

The present invention relates to garden furniture and more particularly to a new and novel type of wheeled garden seat and 15 its method of construction.

The object of the present invention is to provide a garden seat of a new and improved form which is adapted to be shipped in disassembled form and erected by the 20 purchaser.

With this and other objects in view, the various features of the invention consist in certain novel features of construction, combinations and arrangements of parts herein- 25 after described and claimed, the advantages of which will be obvious to those skilled in the art from the following description.

In the accompanying drawings illustrating the preferred form of the invention, 30 Fig. 1 represents a perspective view of a garden seat embodying the features of the invention; Fig. 2 is a fragmentary plan view illustrating the method of rigidly connecting the seat portion to the front and back 35 portions and the mounting of the wheel; Fig. 3 is a section in elevation of the seat upon the line 3—3 of Fig. 1; Fig. 4 is a fragmentary view illustrating a method of connecting the arms to the front and back por- 40 tions of the seat; and Fig. 5 is a similar view illustrating the double mortise joints for interlocking the various supporting members at the four corners of the seat.

The improved form of seat shown in the 45 illustrated embodiment of the invention comprises generally a settee which may be of any suitable design or having any desired ornamentation thereon. The front and back portions of the settee are provided with lon- 50 gitudinally extending shafts positioned slightly below the seat level and extending beyond the settee at opposite ends. At one end, the two shafts are provided with depending bearing members between which are journaled a wheel for transporting the set- 55 tee. The journal bearing for the wheel is

located substantially below the shafts and the wheel is of such diameter that when the settee rests upon the ground the lower portion of the periphery of the wheel is slightly 60 elevated therefrom. The shaft projections at the opposite end of the settee terminate in handles for the purpose of elevating the settee onto the wheel and transporting it from place to place. This type of construc- 65 tion is well suited for lawns, gardens, tennis courts and similar outdoor gathering places where an ornamental and comfortable seat is required. Obviously, by virtue of the wheel construction, the settee may be easily 70 moved to a point best suited for its location or removed to the protection of a building in stormy or winter weather.

The construction of the seat is so designed that it may be transported initially in a 75 compact, disassembled form and thereafter readily erected by the dealer or ultimate user with little skill and effort, the various parts of the seat when completely assembled being rigidly interlocked with one another 80 in such a manner that the seat will withstand severe usage without weakening or serious injury.

Referring to the accompanying drawings, the seat comprises generally a back portion 85 having corner posts 10 and 11 which are rigidly connected by longitudinal members 12 and 13 having the back slats 14 connected therebetween. As will be evident from an inspection of Figs. 1 and 3, the members 12 90 and 13 are mortised into the corner posts 10 and 11, the mortise receiving the upper member 12 being slightly tapered. With this construction, by assembling the longitudinals with opposite ends of the slats received in grooves and thereafter assembling the longitudinals 12 and 13 with the corner posts, the inclination of the longitudinal 12 95 rigidly locks the slats in place through the bending action thereon. Extending length- 100 wise of the back portion below the longitudinal 13 is a shaft 20 mortised into the corner posts at 21 and projecting from opposite ends of the back portion to form respectively a bearing member 22 and a handle 23. The front portion of the seat com- 105 prises front corner posts 25 and 26 of shorter length than the corner posts 10 and 11 rigidly connected by a longitudinally extending shaft 28 projecting beyond the corner posts to form respectively a wheel bearing 30 and 110 a handle 31. Interposed between the front

and back portions and connected thereto is a seat member comprising transverse end supports 35 and a central support 36. The three supports are connected to seat slats 38. As indicated clearly in the drawings, more particularly Figs. 2, 3 and 5, the seat portion is rigidly connected with the front and back portions through a double mortise formed in the corner posts. This double mortise is shown more particularly in Fig. 5, the corner post 26 having a mortise slot 40 which receives the shaft 28 and a second and shallower slot 42 therebeneath which receives a tenon 43 formed on the end support 35. The interlocking joints are identical on each of the four corner posts and upon opposite ends of the supports 35. When the various parts are in assembled position, as indicated in Fig. 3, the end supports 35 are located below the upper faces of the longitudinal shafts and the seat slats are at substantially the level of the shafts. In assembling the construction, a back portion and front portion are assembled with a seat portion and the parts rigidly interlocked by through bolts 50 which pass through preformed openings in the corner posts and shafts and are received in longitudinal slots 52 formed in the end supports. A through bolt is provided at each end of the seat and is locked by a nut 54 located at the back of the rear corner post. With this construction, the through bolts are received in slots formed upon the inner faces of the end supports and thus substantially hidden from view.

The seat is transported by means of a wheel 60 having a hub portion 62 journaled in depending bearing plates 63 and 64, the bearing, as indicated, being substantially below the front and rear shafts. The axle for the wheel extends completely through the rear bearing plate 63, whereas a cover plate 66 is attached to the front bearing plate to cover the front end of the axle. Obviously, in assembling the seat, the wheel and axle are mounted between the bearing plates when the seat portion is assembled with the front and back portions. After assembling the front, back and seat portions, together with the wheel and axle, the seat is completed by mounting arm rests 70 and 71, which, as indicated clearly in Fig. 4, are received in mortises 72 formed in the rear corner posts and are locked to the upper ends of the front corner posts by virtue of mortises 74 formed in the underside of the arm rests. If so desired, the arm rests may be permanently connected to the front and rear corner posts by bolts or screw fastenings 75. From the foregoing description, it will be evident that the seat when disassembled comprises essentially a back portion, a front portion, a seat portion, a wheel and axle, and two arm rests, together with two through

bolts for locking the parts in assembled relation. With this construction, the seat may be transported in a compact disassembled form and readily erected without necessitating any particular skill on the part of the 70 erector. It will be furthermore evident that the construction is simplified, due to the fact that the front and back shafts, the front corner posts, the back corner posts, the arm rests, and the end supports are all interchangeable. 75

While it is preferred to employ the specific construction and arrangement of parts shown and described, it will be understood that this construction and arrangement is 80 not essential except so far as specified in the claims and may be changed or modified without departing from the broader features of the invention.

The invention having been described, what 85 is claimed is:

1. A garden seat comprising supporting corner posts, a seat portion connected therewith, front and back shafts extending longitudinally below the seat portion and projecting beyond the corner posts at opposite ends, handles formed upon the shafts at one end, depending bearing plates mounted upon the opposite ends of the shafts, and a wheel and axle journaled between the bearing plates 90 below the shafts with the wheel normally elevated above the ground when the corner posts are resting thereon. 95

2. A garden seat comprising supporting corner posts, a seat member connected thereto, shafts extending longitudinally of and below the seat member and projecting beyond the corner posts at opposite ends, handles formed upon one end of the shafts, depending bearing members mounted upon the 100 opposite projecting ends of the shafts, a cover plate mounted over the front bearing member, and a wheel and axle journaled between the bearing members below the shafts 105 and with the wheel normally elevated above the ground when the corner posts rest thereon. 110

3. A garden seat comprising a back portion having oppositely disposed corner posts, a shaft extending longitudinally of the back portion and projecting beyond opposite ends thereof, the shaft being rigidly connected to each of the corner posts through a mortise formed in the post, front corner posts, a second shaft extending longitudinally and rigidly connected to the front corner posts through a mortise formed in each post, a seat member having transverse end supports, each end support being received at opposite ends in a portion of the mortise formed in the front and rear corner posts, means for rigidly connecting the front and back portions and seat member together, bearing members depending from the projecting ends of the shafts and a wheel and axle 120 125 130

journaled between the bearing members below the projecting portions of the longitudinal shafts at one side of the seat.

4. A garden seat comprising a back portion having oppositely disposed corner posts, a shaft extending longitudinally thereof and projecting at opposite ends, front corner posts, a shaft extending longitudinally thereof and projecting at opposite ends, a seat member having transverse end supports provided with longitudinal recesses on the inner

sides, a connecting bolt passing through front and rear corner posts and received in the longitudinal recess at each end of the seat member to rigidly lock the front and back portions and the seat member together, a wheel and axle journaled below the shaft extensions at one end, and handles formed upon the opposite ends of the extensions. 15

In testimony whereof I have signed my 20 name to this specification.

GOULD M. CROSBY.
